DESIGN FOR A TOWER

Harold Cohen, Elizabeth, N. J.

Application November 28, 1944, Serial No. 116,591

Term of patent 14 years

(Cl. D13—1)

To all whom it may concern:

Be it known that I, Harold Cohen, a citizen of the United States and a resident of Elizabeth, in the county of Union and State of New Jersey, have invented, a new, original, and ornamental Design for tower, of which the following is a specification, reference being had to the accompanying drawing, forming part thereof.

Fig. 1 is a side elevational view of a tower, showing my new design;

Fig. 2 is a perspective view of a portion of the tower on an enlarged scale; and
Fig. 3 is a top plan view.

I claim:

The ornamental design for a tower, substantially as shown.

HAROLD COHEN.
